Fig. 1

Fig. 2

Fig. 3

Fig. 4

Figure 1 is a view, substantially in perspective, of a Christmas tree skirt embodying my new design, a portion of the trunk of a Christmas tree and surface ornamentation on the uppermost skirt surface being shown in phantom outline for illustrative purposes;

Figure 2 is a developed plan view of the uppermost skirt member of Figure 1;

Figure 3 is a developed plan view of the intermediate skirt member of Figure 1; and

Figure 4 is a developed plan view of the lowermost skirt member of Figure 1.

I claim:

The ornamental design for a Christmas tree skirt, as shown and described.
